CENTER

Delbert A. Gegenheimer, Chicago, and James J.
Kirby, Oak Park, Ill.

Application October 6, 1937, Serial No. 167,580

14 Claims. (Cl. 82—33)

This invention relates to a center and particularly to a center so designed that it automatically and positively achieves a centering effect when a work piece is seated in it and thus achieves 5 concentricity and avoids out of balance and "chatter" in the device in which it is used.

One object is to provide a center for a lathe or other tool in which a work piece may be readily and positively centered when being put 10 into position for work and in which it automatically becomes centered even though the initial seating may be somewhat out of center, and in which it thereafter remains centered automatically by reason of the shape and construction 15 of the centering device itself.

Another object is to provide a device of the type indicated which may be readily removable to permit replacement and change.

Another object is to provide a device in which 20 a special fixture to receive the end of an irregularly or unsymmetrically shaped work piece may be readily put in position in the device as a whole.

Other objects will appear from time to time in 25 the course of the specification and claims.

The invention is illustrated more or less diagrammatically in the accompanying drawing, wherein:

Figure 1 is a longitudinal cross section illustrating 30 one form of the device;

Figure 2 is an end view of the device of Figure 1;

Figure 3 is an elevation of the work receiving member of the device of Figures 1 and 2.

Figure 4 is a modified form of the work receiving member shown in elevation;

Figure 5 is a longitudinal section of a modified form of the work piece receiving member;

Figure 6 is an end elevation of the device of Figure 5;

Figure 7 is a longitudinal section of a specially shaped work receiving member;

Figure 8 is an end elevation of the same showing 45 a work piece in position partially in section, the figure being taken on line 8—8 of Figure 7;

Figures 9 and 10 are generally similar to Figures 7 and 8 by illustrating a receiving member shaped for a circular piece of work;

Figure 11 is a view generally similar to Figure 50 9 showing a modified form of work receiving member in which the work piece is gripped positively.

Figure 12 is an end view of the device of Figure 55 11, being taken in section at line 12—12 of

Figure 11, with parts in section and parts in elevation; and

Figure 13 is a fragmentary longitudinal sectional view with parts broken away and parts in elevation showing a modification of the device 5 of Figure 9.

Like parts are designated by like symbols throughout the specification and drawing.

1 is the housing of a hollow and preferably tapered shank 2 which may be interiorly threaded as at 3 to receive a rod 4 correspondingly threaded as at 5 and slotted as at 6. The rod may be used to remove the work receiving assembly from the housing. For that purpose a tool such as the screw driver is inserted in the slot 6, the rod 4 rotated and forced inwardly to contact the work receiving member to force it out. The housing includes a larger hollow section 7 which as shown has within it a raised annular portion 8 which extends somewhat above the floor or bottom 9 of the interior of the section 7. The wall of the section 7 is perforated to receive a lubricating cup 10 which as shown has a spring 11 tending normally to seat a ball 12 against the edges of a perforated member 13, so that the ball normally stays in the closing position but may be readily pushed inwardly against the resistance of the spring to permit lubrication. Adjacent its outer edge, section 7 may have an inclined groove 14 in which a spring ring 15 may be seated. The spring ring serves to hold the parts within the section 7 against accidental displacement and may be removed to permit disassembly of the device.

There are seated within the hollow section 7 two bearings. There is thus a roller bearing comprising an outer race 16 which is positioned against the inner surface of the outer wall of the section 7, and an inner race 17. Tapered rollers 18 are positioned between the two races 40 to contact them both. A ball bearing is positioned outwardly of the roller bearing and comprises an inner race 19 preferably in contact with the inner race 17 of the roller bearing and an outer race 20 normally in contact with the inner 45 surface of the section 7. The races 19 and 20 are suitably shaped to receive the balls 21. As shown, the inner races 17 and 19 have preferably the same interior diameter so that they readily receive the reduced shank 22 of the work piece 50 receiving member. This member is preferably provided with an enlarged portion 23 which has conical depression 24 formed within it, the walls of which are formed with an inclination of 30 degrees to the longitudinal axis of the device as 55

a whole. The angle of the inner face of the outer roller bearing race 16 is approximately the same. As shown in Figure 1, a work piece 25 is positioned within the depression 24. Experience has shown 5 that this work piece will automatically be properly centered within this depression, even though initially it may have been inserted carelessly and without proper centering. The arrangement of the roller bearing has been shown by experience 10 to accomplish automatically the proper centering of the work piece holder 22, 23 within the assembly. The angularity of the races of the roller bearing is such that they accomplish this centering automatically and certainly. The combination 15 of a roller bearing with a ball bearing permits this because the ball bearings, being round, set up no effective resistance to the centering and permit that relatively minute movement or accommodation which is necessary to accomplish 20 with certainty the centering.

In the modified form of the device shown in Figure 4, the shank 22 is the same as that shown in Figures 1 and 3, but instead of the depression a conical outwardly projecting member 26 is used. 25 This type of center member or work piece receiving member is of particular advantage where the work piece has a center already properly marked on it, as is sometimes the case. Then this center mark is positioned on the point 27 of 30 the member 26.

In the further modification of Figure 5, the device is generally like that shown in Figure 3, but there are provided on the inner face of the conical depression 24 a plurality of raised lands 35 or guides 28. The particular advantage of this construction is in connection with work piece which, while generally symmetrical, may have "burrs" or other slight irregularities. The work piece may be so positioned that the burr or other 40 irregularity does not contact one of the lands 28 and is held out of contact with the inner face of the conical depression 24. Thus, even though the end of the work piece is irregular, proper centering may occur.

45 Where it is desired to use the device in connection with a work piece which is not symmetrical or not round, the work piece receiving member may be made up specially and given a particular shape to handle the desired work piece. Thus, as shown in Figures 7 and 8, the shank member 22, instead of having a symmetrical projection, such as the members 23 or 26, has a projection 29 which is generally rectangular as shown particularly in Figure 8 and is provided with a depression 30 having inner faces 31 tapered inwardly preferably at the same inclination as that given to the inner faces of the conical depression 24. The work piece is indicated as comprising a round portion 32 which is 50 arranged co-axially with the portion 22 and having a non-round portion 33 received in the depression 30 of the member 29. The shape of these parts serves to center the portion 32 with respect to the work receiving device, and as in 55 the case of the earlier forms the work receiving piece 22, 29 is centered by the bearings shown in Figure 1.

A further modified form is indicated in Figures 9 and 10, and in that the member 22 carries a 60 hollow receiving portion 34 which in that case is round, as shown in Figure 10, but is out of center with respect to the stub portion 22. It is hollow or provided with a depression 35 having inwardly sloping walls 36 whose angle of inclination 65 is preferably the same as that of the walls

of the depression 24. There is shown seated in this member a work piece having a section 37 which is co-axial with the stub portion 22. This work piece also carries two or more members 38 which are not co-axial with the section 37 or the 5 stub 22.

There is shown in Figures 11 and 12 a further modified form in which the stub section 22 carries a work piece receiving member 39 which is generally elliptical as shown in Figure 12 and is 10 hollow in its interior, the inner walls being preferably straight sided as at 40. The member 39 is split as at 41 and terminates in a pair of perforated ears 42. The work piece having been inserted, may be gripped by a bolt 43. In that 15 form, the work piece comprises a section 44 co-axial with the stub 22 and an elliptical section 45 which is not co-axial with that member.

Figure 13 illustrates a possible use of the form of the device shown in Figures 11 and 12. As 20 there shown, the device proper is that of the form shown in Figures 1, 2 and 3. The work holding piece is that shown in Figures 11 and 12.

It will be realized that whereas I have herein shown and described a practical operative 25 device, nevertheless many changes might be made in the size, shape, number and disposition of parts without departing from the spirit of the invention. In particular, the shape of the special fixtures shown in Figures 7 to 13, inclusive, might 30 be almost indefinitely varied, and the combination of them, such as shown in Figure 13, might also be varied. While these fixtures in some sense and in some degree give a centering effect, the main centering is in all of the forms of the device 35 accomplished by the arrangement of the anti-friction bearings, and therefore the invention is not limited to any particular arrangement of specific fixture or device to grip or to be adapted to the end or the particular shape of a work piece. 40

The use and operation of the invention are as follows:

The form of the device shown in Figure 1 may be considered as typical, although the work contacting piece of Figure 4 might be substituted for 45 that of Figures 1, 2 and 3. Whatever the particular shape of the member or fixture which contacts the work, the operation of the device is generally the same. The work is initially centered as accurately as can be conveniently done on the 50 fixture or piece which contacts it. The form shown in Figure 4 is particularly adapted for use where the work piece has a center marked on it. One example of such a use is in connection with armatures in which the shaft frequently 55 has a center definitely marked. Where that is the case, the form of Figure 4 would be used and the point 27 engages the marking or depression which marks the center of the work piece. Where the center is not marked, ordinarily one of the 60 other forms of work receiving pieces will be used. That of Figure 1 is typical. Because of the inclination of the walls of the depression, the work piece is automatically, by the mere act of penetration, brought into an approximate center position. The actual and final centering is accomplished automatically by the shape and arrangement of the bearings. The roller bearing particularly by reason of the inclination of its races, inevitably causes accurate centering of the portion 22. Should slight lateral tilting or adjustment be necessary, the ball bearings permit it, because their contact with their races is such as to permit some tilting or adjustment.

Therefore, the roller bearings accomplish a 75

centering and the ball bearings cooperate with the roller bearings to permit this centering. A plurality of roller bearings would ordinarily work against each other and one would tend to counteract the effect of the other. If a plurality of ball bearings were used, they would accomplish no centering effect. It is important, therefore, to use one type of bearing which accomplishes a centering effect and another type of bearing which will not interfere with that centering effect but will permit it to occur freely and at the same time will furnish adequate anti-friction support for the member 22 and the part 23.

16 Where any of the special fixtures are to be used, they are shaped to be adapted to the particular shape of the end of the work piece which they engage, and while rectangular, round and elliptical shapes have been shown, the invention 20 is not illustrated to them and any shape at all might be used. It is preferable, although not necessary, to give the inner walls of these fixtures an inclination which is approximately the same as that of the depression 24 and thus furnishes 25 to some degree a centering effect within the fixture itself. The form of Figure 11 does not accomplish a particular centering purpose but merely furnishes a means for gripping the enlarged and out of center end of the work piece 30 so that the portion 22, which corresponds to the portion 22 of Figure 1, may fit readily into the depression 24 for centering.

The operation of the form of Figures 5 and 6 is generally the same as that of Figures 1, 2 and 35 3, except that the raised portions 28 furnish a clearance so that if the end of the work piece should be slightly deformed or should be nicked or carries burrs or other projections, the work 40 piece can be so positioned that these do not contact the raised members 28 and that those members contact only the undeformed portions of the end of the work piece, and thus proper centering is accomplished in spite of the nicking, burring or other deformation.

45 We claim:

1. In a tool center, a hollow housing member having an open-ended hollow enlargement, a center piece positioned therein for rotation with respect thereto, a roller bearing positioned within said enlargement and about said center piece, having its inner race engaging said center and its outer race engaging said enlargement, the outer race being inclined inwardly toward the axis of said housing, and a roller bearing positioned outwardly with respect to said roller bearing toward the open side of said enlargement, and having its inner race engaging said center and its outer race engaging the inner wall of said enlargement, and means for retaining said bearings in position.

2. In a tool center, a hollow housing member having an open-ended hollow enlargement, a center piece positioned therein for rotation with respect thereto, a roller bearing positioned within said enlargement and about said center piece, having its inner race engaging said center and its outer race engaging said enlargement, the outer race being inclined inwardly toward the axis of said housing at an angle of approximately thirty degrees with respect thereto, and a roller bearing positioned outwardly with respect to said roller bearing toward the open side of said enlargement, and having its inner race engaging said center and its outer race engaging the inner wall of said enlargement, and means for retaining said bearings in position, said center piece

wall of said enlargement, and means for retaining said bearings in position.

3. In a tool center, a hollow housing member having an open-ended hollow enlargement, a center piece positioned therein for rotation with respect thereto, a roller bearing positioned within said enlargement and about said center piece, having its inner race engaging said center and its outer race engaging said enlargement, the outer race being inclined inwardly toward the axis of said housing, and a roller bearing positioned outwardly with respect to said roller bearing toward the open side of said enlargement, and having its inner race engaging said center and its outer race engaging the inner wall of said enlargement, and means for retaining said bearings in position, said center piece having a generally conical cavity formed in it, the sides of which incline inwardly at an angle of approximately 30 degrees with respect to the central axis of the center as a whole.

4. In a tool center, a hollow housing member having an open-ended hollow enlargement, a center piece positioned therein for rotation with respect thereto, a roller bearing positioned within said enlargement and about said center piece, having its inner race engaging said center and its outer race engaging said enlargement, the outer race being inclined inwardly toward the axis of said housing at an angle of approximately thirty degrees with respect thereto, and a roller bearing positioned outwardly with respect to said roller bearing toward the open side of said enlargement, and having its inner race engaging said center and its outer race engaging the inner wall of said enlargement, and means for retaining said bearings in position, said center piece having a generally conical cavity formed in it, the sides of which incline inwardly at an angle of approximately thirty degrees with respect to the central axis of the center as a whole.

5. In a tool center, a hollow housing member having an open-ended hollow enlargement, a center piece positioned therein for rotation with respect thereto, a roller bearing positioned within said enlargement and about said center piece, having its inner race engaging said center and its outer race engaging said enlargement, the outer race being inclined inwardly toward the axis of said housing, and a roller bearing positioned outwardly with respect to said roller bearing toward the open side of said enlargement, and having its inner race engaging said center and its outer race engaging the inner wall of said enlargement, and means for retaining said bearings in position, said center piece having a generally conical depression and a plurality of raised "lands" formed in its inner wall and converging toward its center.

6. In a tool center, a hollow housing member having an open-ended hollow enlargement, a center piece positioned therein for rotation with respect thereto, a roller bearing positioned within said enlargement and about said center piece, having its inner race engaging said center and its outer race engaging said enlargement, the outer race being inclined inwardly toward the axis of said housing at an angle of approximately thirty degrees with respect thereto, and a roller bearing positioned outwardly with respect to said roller bearing toward the open side of said enlargement, and having its inner race engaging said center and its outer race engaging the inner wall of said enlargement, and means for retaining said bearings in position, said center piece

having a generally conical depression and a plurality of raised "lands" formed in its inner wall and converging toward its center.

7. A center piece for tools comprising a member having a cavity generally conical and means within said cavity for centering a work piece, said means comprising a plurality of raised "lands" lying within the cavity and converging toward its center, said lands comprising the seating surface 10 of a work piece within said cavity.

8. A center piece for tools comprising a member having a cavity generally conical and means within said cavity for centering a workpiece, said means comprising an uneven number of raised

15 "lands" lying within the cavity and converging toward its center, said lands comprising the seating surface of a work piece within said cavity.

9. In combination in a tool center, an elongated member and a hollow open-ended enlargement, a 20 center piece positioned for rotation within said enlargement and a plurality of anti-friction bearings positioned within said enlargement and supporting said center, the bearings comprising a roller bearing and a ball bearing, each arranged 25 with its inner race contacting the center and its outer race contacting the inner wall of the enlargement, the ball bearing being positioned outwardly toward the open end of the enlargement beyond the roller bearing.

10. In combination in a tool center, an elongated member and an integral hollow open-ended enlargement, a center piece positioned for rotation within said enlargement and a plurality of anti-friction bearings positioned within said 30 enlargement and supporting said center, the bearings comprising a roller bearing and a ball bearing, each arranged with its inner race contacting the center and its outer race contacting the inner wall of the enlargement, the ball bearing being positioned outwardly toward the open

end of the enlargement beyond the roller bearing.

11. In combination in a tool center, an elongated member and an integral hollow open-ended enlargement, a center piece positioned for rotation within said enlargement and a plurality of anti-friction bearings positioned within said enlargement and supporting said center, the bearings comprising a roller bearing and a ball bearing, each arranged with its inner race contacting the center and its outer race contacting 10 the inner wall of the enlargement, the ball bearing being positioned outwardly toward the open end of the enlargement beyond the roller bearing, the outer race of the roller bearing being inclined inwardly toward the axis of the center as a whole 15 at an angle of approximately 30 degrees to the line of the axis of the apparatus.

12. A center piece for tools comprising a member having a generally rounded shank and a cavity opening away from said shank and out of 20 center with respect to said shank, the walls of said cavity tapering inwardly at an angle of approximately 30 degrees with respect to the axis of said shank.

13. A center piece for tools comprising a member having a generally rounded shank and a cavity opening away from said shank, the walls of 25 said cavity tapering inwardly at an angle of approximately 30 degrees with respect to the axis of said shank, said cavity being of generally rectangular cross section.

14. A center piece for tools comprising a member having a generally rounded shank and a cavity opening away from said shank, the walls of 30 said cavity tapering inwardly at an angle of approximately 30 degrees with respect to the axis of said shank, said cavity being of generally elliptical cross section.
